UNITED STATES PATENT OFFICE.

THOR GUSTAF THÖRNBLAD, KARL HJALMAR WARFVINGE, AND VICTOR GABRIEL WERNER, OF STOCKHOLM, SWEDEN.

INDUCTIVE WIRELESS-TELEPHONE SYSTEM FOR RAILROADS AND THE LIKE.

1,216,887.

Specification of Letters Patent.

Patented Feb. 20, 1917.

Application filed June 6, 1914. Serial No. 843,362.

To all whom it may concern:

Be it known that we, THOR GUSTAF THÖRNBLAD, KARL HJALMAR WARFVINGE, and VICTOR GABRIEL WERNER, subjects of the 5 King of Sweden, and residents of Stockholm, in the Kingdom of Sweden, have invented new and useful Improvements in Inductive Wireless-Telephone Systems for Railroads and the like, of which the following is a specification, reference being had to the drawing accompanying and forming a part hereof.

A telephonic system with the same purpose as ours, and which may also be called a 15 system partly wireless and partly with use of wire, has previously been designed. However, this system shows practical disadvantages so great, that it must be supposed from the mere description of the same, that said 20 system has never been put to practical tests, nor could it be mentioned as a solution of the problem of communication between trains and stations. In short, the arrangement is the following, based on the principle 25 of induction from one coil to another. On a railroad car—or it may, generally speaking, be a vehicle—there is placed a coil of comparatively small size. Connected to said coil is an ordinary microphone and a source 30 of electrical supply when speaking, and a receiver when hearing. Along the railroad—or, when a vehicle, the path of travel—is an extensive coil stretched out and erected in the shape of a frame with its long sides running along and parallel to the path of travel. Connected to this great coil is an ordinary microphone and a convenient source of electrical supply, when speaking to the vehicle, and a receiver when hearing. Thus, electrically, the system described consists in the 40 induction from a smaller coil to a greater, and vice versa. It is stated as an essential part of this system, that the greater coil consists of a plurality of convolutions, and it is 45 obvious that this system will result in no telephonic communication, if the greater coil does not consist of a plurality of convolutions. It is evident, however, that such an arrangement as that described, comprising 50 a great coil with many convolutions surrounding the whole field in which telephoning is to take place, is connected with great disadvantages. Thus, a system of such a kind must result in immense costs of erect-

ing and maintaining, on account of the mentioned coil around the path of travel.

Being aware of this disadvantage we have devoted our efforts to invent such a system that the use of a stationary coil is entirely eliminated.

After elaborate experiments we have finally invented a system, whereby instead of the mentioned troublesome and costly coil-building we make use of the ordinary telephone or telegraph wires running along the railroad or we may use an especially erected single-wire line. An essential feature of our system in contradistinction to that described is, that we may use a single-wire line, when in the other system no results can be obtained without an unpractical coil-building. However, no communication can be established by means of such a single-wire line with the use of an ordinary microphone, as in the system referred to. It is essential and necessary here to make use of a microphone belonging to another class viz. a so called "strong-current microphone." Microphones belonging to the so called strong-current microphone class differ from ordinary microphones in this essential feature, that microphones of the first-named kind, due to characteristic arrangements, permit a considerably greater direct current energy to be transferred into alternating current energy than is possible with the ordinary microphone. All the characteristic arrangements in strong-current microphones, referred to above and making possible the use of considerably stronger sources of electrical energy, have for aim, whatever they may be, to enable the strong-current microphone to withstand the influence of the heating effect of the electrical current upon the microphone contact material.

In the accompanying drawing we have shown diagrammatically different forms of construction of our invention.

Referring to Figure 1, 1 represents a telephone or telegraph wire along the railroad track, or it may be a wire especially erected. This wire is grounded at both ends, but in some instances it may be preferable to provide the same with a returning part, *i. e.* a wire or conductor between the points 2 and 3. To this wire 1 is connected a telephone receiver 4 at a station on the railroad. On a car of the train there is located a circuit,

which includes a strong-current microphone 5, an induction frame 6, and a battery 7. The induction frame 6 consists of several turns of insulated wire and is preferably arranged on the top or outside of the car. From the battery 7 strong currents are flowing through the circuit. It is obvious that when speaking in the microphone 5 pulsating currents will be produced in the circuit, which by induction from the induction frame 6 produce alternating currents in the wire 1, which will cause the speech to be heard in the receiver 4 at the station.

Fig. 2 illustrates an arrangement whereby it is possible to transmit speech from the railroad station to a moving train. The wire 8 along the railway track is preferably grounded at both ends and at one end, suitably at the railroad station, there is connected to the wire 8 a strong-current microphone 9 and a powerful battery 10. On a car of the train is located an induction frame 11, to which a receiver 12 is connected in series. The pulsating currents produced in the wire 8 when speaking into the microphone 9 will produce corresponding alternating currents in the induction frame 11 on the train, which will cause the speech to be heard in the receiver 12.

By combining the arrangement shown in Fig. 1 for transmitting speech from the train to the station and that shown in Fig. 2 for transmitting speech from the station to the train, the arrangement illustrated in Fig. 3 may be obtained, by means of which it is possible to talk from the train to the station and vice versa. At the station at one end of the wire 13 the switch 14 is connected to the same by means of which either the receiver 15 or the strong-current microphone 16 and the battery 17 may be connected in series with the wire 13. On a car of the train is located an induction frame 18, to the circuit of which by means of a switch 19 may be connected either a receiver 20 or a strong-current microphone 21 and a powerful battery 22. In the shown positions of the switches 14 and 19 these are set for speech to be transmitted from the train to the station. When it is desired to talk from the station to the train the switches 14 and 19 are moved over to their positions shown in dotted lines, when the microphone 16 and the battery 17 will be connected with the wire 13, and the receiver 20 will be connected to the induction frame 18.

In Fig. 4 we have illustrated another arrangement for speaking from the train to the station and vice versa. The apparatus at the station is connected in the same manner as shown in Fig. 3 and comprise a switch 23, a strong-current microphone 24, a powerful battery 25, and a receiver 26. On a car of the train there are arranged two

induction frames 27 and 28, of which the frame 27 is connected to the strong-current microphone 29 and powerful battery 30, the other frame 28 being connected in series with a receiver 31. The frames 27 and 28 are preferably of oblong shape and arranged in the longitudinal direction of the car, *i. e.* so that their long sides will be approximately parallel to the wire 32 running along the railroad track, and so that their short sides are abutting. By this arrangement the advantage is attained that it is possible to speak from the train and at the same time to hear the speech in the receiver 31, without having to operate a switch.

Fig. 5 illustrates an arrangement whereby two wires 33 and 34 ordinarily used for telephoning between two stations 35 and 36 on the railroad, may be used for transmitting speech from a train to other stations. The induction frame and the apparatus on the train are indicated by 37 and 38 respectively. 39 and 40 represent two stations provided with apparatus as shown in Figs. 3 and 4. These stations are connected to the wires 33 and 34 by a duplex connection familiar to those skilled in the art, and we do not deem it necessary to further describe the same. By means of switches 41 and 42 these stations 39 and 40 may be connected to or disconnected from the wires 33 and 34, ground connections 43 and 44 being provided for grounding that end of the line where the apparatus at the station is not connected to the wires. It is obvious that telephoning may take place from the train over the wires 33 and 34 to any of the stations 39 and 40 without disturbing the transmitting of messages from one of the stations 35 and 36 to the other.

In Fig. 6 we have shown a suitable way of connecting a wire along the railroad track to several stations in such manner that the wire will be divided in sections, in order to make the circuits for each station as short as possible. A, B, C and D represent four stations on the railroad, the stations A and B being each provided with one of our telephone apparatus 45 and 46, and the stations C and D each with two 47, 48, 49 and 50. The wire 51 along the railroad track is, as shown in the drawing, divided in sections between the stations, the ends of each section being connected to the apparatus at the station either by means of switches 52 and 53, as shown at the stations A and B, or directly as at the stations C and D. At points intermediate the stations the wire 51 is grounded. 54, 55 and 56 represent trains moving on the railroad. It is evident from the drawing that in the shown positions of the switches 52 and 53, the station A is in communication with the train 54 and the station B with the train 55. The train 56 is in communication with the apparatus 49 13

at the station D. When all trains have moved into the right hand halves of the sections the train 54 will be in communication with the station B, after the switch 53 has been moved over to the dotted position, the train 55 will be in communication with the apparatus 47 at the station C, and the train 56 with the apparatus 50 at the station D.

We claim:

10 In an inductive wireless telephone system for railroads, the combination of a circuit on the train comprising a strong-current microphone, a receiver, and a source of electrical energy, and a stationary circuit

formed by telegraph or telephone wires 15 along the railroad track used for the ordinary telegraph and telephone traffic and comprising a strong-current microphone, a receiver, and a source of electrical energy, said circuits being in inductive relation to 2 each other, substantially as and for the purpose set forth.
